Nelson W. Howard

UNITED STATES PATENT OFFICE.

ARTHUR BATES, OF LEICESTER, ENGLAND, ASSIGNOR TO UNITED SHOE MACHINERY CORPORATION, OF PATERSON, NEW JERSEY, A CORPORATION OF NEW JERSEY.

LASTING MACHINE.

Application filed June 18, 1920. Serial No. 389,966.

To all whom it may concern:

Be it known that I, ARTHUR BATES, a subject of the King of England, residing at Leicester, Leicestershire, England, have invented certain Improvements in Lasting Machines, of which the following description, in connection with the accompanying drawings, is a specification, like reference characters on the drawings indicating like parts in the several figures.

This invention relates to machines for working uppers over lasts. The invention is herein shown and described as applied to a hand method lasting machine of the type disclosed in United States Letters Patent No. 584,744, granted June 15, 1897, upon application of Ladd & McFeely. It is to be understood, however, that the invention is not limited in its application to machines of this type.

The machine of said prior patent comprises a gripper and mechanism for imparting to the gripper a yielding updraw motion to pull the upper yieldingly about the last and an overdraw motion to lay the pulled upper down upon the last; it comprises also means for giving a plaiting motion to the gripper to plait the upper which can be used in operating upon such parts of the shoe where plaiting movement is desirable. In the said machine the plaiting motion of the gripper is compound, being made up of a turning or twisting motion and a lateral motion. It is to be understood, however, that the term "plaiting motion" of the gripper is intended to cover either the twisting motion alone or the lateral motion alone as well as the compound motion before mentioned.

A feature of the present invention consists in means for effecting one portion of the upper pulling movement unyieldingly and another portion yieldingly. As herein shown one portion of the upper pulling movement is effected yieldingly as for instance through a suitable spring, and another portion is effected unyieldingly as for instance by a positive connection between the gripper and its operating cam. Preferably and as herein shown the upper pulling movement is continuous, means being provided to cause the positive actuation of the gripper to become effective automatically at a predetermined point in the upper pulling movement so that a continuous divided

updraw pull is effected, one portion of which is yielding and another portion positive.

A further feature of the invention consists in means under the control of the operator for varying the point in the upper pulling movement when the positive pulling of the upper will begin which means may be employed if desired to discontinue entirely the positive portion of the upper pulling movement or to eliminate the yielding portion of the upper pulling movement and render the pulling movement entirely positive.

In lasting the toes of shoes upon machines of the hand method type above referred to it is frequently desirable to employ means for slitting the upper so as to cause the plaits of the upper material at the toe to lie more smoothly upon the innersole, particularly when operating upon uppers of stiff or thick material. A machine organized for such work is disclosed in United States Letters Patent No. 931,809, granted August 24, 1909, on application of E. A. Stiggins. In operating machines of the type disclosed in the patent to Stiggins it has been found in practice that the movement imparted to the gripper through the yielding mechanism provided by the machine is not always sufficient to carry the gripper out of the way of the slitting mechanism so that the knives may strike the gripper and become dulled, thus necessitating the delay of sharpening them again. A feature of the present invention consists in an organization comprising means for effecting the updraw pull of the gripper at first yieldingly and then positively and means for slitting the upper after the positive updrawing of the upper has been initiated. By this organization there is full assurance that the gripper will be carried beyond the slitting knives so that there will be no danger of the knives engaging the gripper during their slitting action.

In machines having the general organization of that disclosed in the patent first above mentioned it is desirable to provide a construction and arrangement such as that disclosed in United States Letters Patent No. 1,060,967, granted May 6, 1913 upon my application, wherein the plaiting movements imparted to the gripper begin prior to the overdraw movements, this arrangement being particularly advantageous in lasting the toe of a shoe where the excess of upper material is effectively disposed in lasted posi-

tion by the timing of the plaiting movements as described in my said patent. In connection with the toe lasting effected by the machine of my prior patent it is particularly 5 desirable to employ slitting mechanism such as that disclosed in the above mentioned patent to Stiggins. Heretofore, however, it has been found impracticable to employ the slitting mechanism in combination with the 10 plaiter timing of my prior patent because of the difficulty in avoiding contact of the slitting knife with the gripper. This difficulty is overcome by the present invention. Accordingly a further feature of the invention 15 consists in an organization including means for initiating the plaiting movements prior to the overdraw movement, means for slitting the upper, and means for effecting the updraw pull first through yielding 20 means, and then through unyielding means or positively. By this organization the plaiting movement is begun during the later unyielding portion of the pull so that the gripper is out of the way of the slitting 25 knife when it operates to slit the upper preferably at the completion of the updraw movement.

Still another feature of the invention consists in an organization including means for 30 initiating the plaiting movements of the gripper during the updraw movement and means for effecting the final portion of the updraw movement positively.

The organization disclosed in my said 35 prior patent includes means for giving the wiper or tack carrier a step-by-step movement with a pause between the steps. A further feature of the present invention consists in the combination of means for 40 moving the wiper or tack carriers step by step with a pause between the steps and means for effecting the updraw first yieldingly and then positively. Preferably and as shown, the construction and arrangement 45 is such that the wiper or tack block advances to hold the upper in engagement with the edge only of the shoe bottom and then pauses during the positive end portion or "finale" of the updraw, allowing the stock 50 to be drawn more tightly over the last before advancing to wipe it down on the last bottom.

In the organization disclosed in my afore- 55 said prior patent and as herein shown, means is provided for repeating the plaiting movement of the gripper in a single cycle of the machine. Accordingly a still further feature of the invention consists in 60 means for repeating the plaiting movement of the gripper or wriggling the gripper, and means for effecting the final portion of the updraw positively. Preferably the repeated plaiting movements overlap the period of final unyielding up- 65 draw and the upper is thus more thoroughly

tensioned and the plait more effectively produced and carried nearer to the edge of the last where, preferably, at this time the upper is being held to the last by the wiper after its first advance and before its final 70 wiping movement to lay the plait on the shoe bottom.

These and other features of the invention will appear more fully from the following 75 description, when read in connection with the accompanying drawing, and will be pointed out in the appended claims.

In the drawing.

Fig. 1 is a view in perspective of a machine 80 embodying the present invention, the frame and certain parts being omitted for the sake of clearness in illustration.

Fig. 2 is a side elevation on a larger scale 85 of parts shown in Fig. 1, and

Fig. 3 is substantially a plan view showing 90 a slitting knife and movements of the gripper in their operation on a shoe upper.

In its general organization the machine in 95 which the present invention is embodied is similar to that disclosed in the Ladd & McFeeley patent above mentioned.

As shown in the drawing the gripper 100 operating mechanism comprises an updraw lever 10 pivoted at 12 to the machine frame. A gripper 14, comprising respectively fixed and movable jaws 16 and 18, is hung by its shank 20 to the forward end of the lever and the rear end of the lever is operated by a slide 22 carrying a cam 105 roll 24 which engages a cam path 26 in a cam block 28. The slide 22 has fixed thereto a stem or rod 30 extending loosely through a block 32 to which bifurcations of the rear end of the lever 10 are pivoted at 34. The rod 30 extends loosely through a block 36 and a helical spring 38 is located on the rod between the block 36 and an adjusting nut 40. Between the block 36 and the block 32 is a wedge 42 which may be moved by a rod 44 extending to the front 110 of the machine to vary the normal tension of the spring 38. The above construction will be recognized as usual in machines of this type and is for the purpose of giving a yielding quality to the updraw movement of the gripper. In accordance with the 115 present invention means is provided for imparting a positive or unyielding quality to the updraw movement of the gripper for any desired part of the updraw movement of the cam slide 22. This is effected, in the illustrative embodiment of the invention, by providing on the front face of the block 32, to which the updraw lever 10 is pivoted, a series of upwardly directed ratchet teeth 45 with which a pawl member 46 co-operates. The pawl member 46 is pivoted at 48 to the slide 22 and has a tooth 50 which is urged 120 toward the teeth 45 by a spring plunger 52 mounted in the updraw lever 10 in position

125

130

135

to engage the front face of the pawl member 46. Means is provided for holding the pawl member so that its tooth 50 will be out of engagement with the teeth 45 for any desired portion of the movement of the slide 22 and will then allow it to engage said teeth and cause the downward pull of the cam slide 22 to be transferred directly and positively to the gripper, thus causing the updraw to be positively effected. As shown, this means comprises a plate 52 having an opening through which the upper end of the pawl member 46 extends. The member 46 has an inclined cam face 54 which, at a predetermined time in the downward movement of the slide 22, which of course carries the pawl member 46 with it, allows the pawl tooth 50 to engage the teeth 45 so that the remainder of the movement of the slide 22 is transmitted positively to the lever 10 to effect a positive updraw movement of the gripper 14.

To provide for varying the point in the cycle of the machine when this positive updraw movement will begin the plate 52 is arranged on a slide 56 mounted for vertical movement in a bracket 57 on the machine frame. Vertical movement of the plate 52 will of course cause the tooth 50 to engage the teeth 45 earlier or later in the cycle of the machine. In order that the slide 56 may be conveniently moved by the operator to vary at will the amount of positive movement imparted to the gripper, a screw 58 is rotatably mounted in the bracket 57 at 59 and has threaded engagement with the slide 56. Fixed to the upper end of the screw 58 is a miter gear 62 which is engaged by a miter gear 64 fixed to a shaft 66 which is suitably supported for rotation in the machine frame and extends to the front of the machine where it is provided with a thumb head 68 by which it may be turned to adjust the plate 52 vertically and thus vary the time in the cycle when the tooth 50 will engage one of the teeth 45 and cause the remainder of the updraw to be positively effected.

This positive movement of the updraw, after the yielding portion of the updraw has taken place, has been found very effective in dealing with short or scant uppers and uppers of heavy material on welt and McKay work, and has been found especially desirable in combination with the following organization: The overdraw movement of the gripper is effected by a spring 70 acting on a thrust rod 72, movement of which is controlled by a cam on the rear face of a cam block 74. The plaiting movements of the gripper, including the lateral and twisting movements, are imparted by a mechanism of the usual construction operated by a cam path 76 formed in the front face of the cam block 74. The timing of the overdraw and

plaiting cams with relation to the updraw cam 28 is such that the plaiting motion will begin before the overdraw motion occurs and during the updraw motion of the gripper. In order that the plaiting motion may be repeated a plurality of times during the operation of the machine to produce a wriggling motion of the gripper, the cam path 76 is provided with a plurality of undulations so as to actuate the plaiting mechanism a plurality of times during one rotation of the shaft 78. A tack carrier 80, the lower face of which constitutes the wiper and which is actuated through a slide 82 and lever 84 by a cam path 86, is made to advance in two steps the first of which occurs at about the time the yielding updraw movement is concluded to hold the upper against the last and to avoid the extension of plaiting wrinkles beyond the edge of the last. The second and final step of the wiper occurs after the unyielding portion of the updraw has taken place and after the plaiting movement has progressed far enough to enable the wiper to lay or press the plaited upper down upon the shoe bottom in lasted position, after which the upper may be secured by the usual mechanism which drives a tack through the tack carrier 80 to secure the upper in lasted position.

In lasting uppers of heavy material, especially at the toe, it is frequently desirable to slit the upper so that the upper can be laid more smoothly upon the innersole. In Fig. 1 the machine is shown as provided with toe slitting mechanism organized substantially in accordance with the disclosure of the above-mentioned patent to Stiggins. In this construction two slitting knives 90 and 92 are provided which are operated one at a time to slit the upper in a direction toward its edge. The setting of the knee lever to cause plaiting movements to be imparted to the gripper, by which it is moved laterally toward the right and turned in a counter-clockwise direction, as shown in Fig. 3, will push on a rod 91 connected to a slide 93. The slide 93 has a cam slot 95 engaged by a pin on a transverse slide 97 in which is a vertical groove 99. This groove is engaged by a pin 101 extending through an actuator bar 94. Forward movement of the rod 91 by the knee lever will, through the mechanism described, swing the actuator 94 into engagement with a rack bar 96 which is connected by segments 98, 100 with a rack 102 connected with the knife 90. The construction is such that movement of the actuator 94 vertically by an appropriate cam on the cam shaft causes the knife 90 to advance to a position in front of the gripper and out of contact with the work, then to move toward the work and to return in a path which carries the blade of the knife through the stock and slits it toward the edge of the stock, the

knife then returning to initial position, the mechanism for effecting this being fully disclosed in said Stiggins patent.

When the plaiting movements are in the reverse direction the slitting knife 92 will automatically be thrown into operation by movement of the actuator 94 into engagement with a rack bar 97. In the present construction the organization is such that the slitting knife operates upon the stock in such timed relation to the final or unyielding portion of the updraw that the gripper will be out of the way of the knife in its cutting movement. For this purpose the actual slitting movement of the knife may take place just after the positive updraw movement has been effected, though of course there may be more or less overlapping of the final updraw and the slitting operation provided the timing is such that the slitting knife will avoid contact with the gripper. Preferably, also, the plaiting movement has at least been initiated prior to the slitting action of the knife since the plaiting movement of the gripper disposes the upper on the side of the gripper where the slitting is to be effected in such a position as to enable the slitting knife to perform its work more advantageously.

Having thus described my invention, what I claim as new and desire to secure by Letters Patent of the United States is:

1. An upper pulling machine having, in combination, a gripper, gripper operating mechanism for imparting a yielding pull to the upper, and means becoming effective during the pull for rendering the pull positive.

2. An upper pulling machine having, in combination, a gripper, gripper operating mechanism for imparting a yielding pull to the upper, and means becoming effective during the pull for causing the yielding quality of the pull to be eliminated.

3. An upper pulling machine having, in combination, a gripper, gripper operating mechanism for imparting a yielding pull to the upper, and means becoming effective during the pull for causing the end portion of the pull to be positively effected.

4. In a machine of the class described, the combination of a gripper, means for giving the gripper a yielding updraw movement, means for giving the gripper during the updraw an overdraw movement, and means becoming effective during the updraw for rendering the updraw unyielding.

5. In a machine of the class described having an updrawing gripper, the combination of an updraw spring, and means becoming effective automatically during the action of the spring to prevent further action of said spring.

6. In an upper pulling machine, the combination of an upper pulling gripper, and

means for effecting a continuous divided updraw pull one portion of which is positive.

7. In an upper pulling machine, the combination of an upper pulling gripper, and means for effecting a continuous divided updraw pull one portion of which is positive and another portion yielding.

8. In an upper pulling machine, the combination of an upper pulling gripper, means for giving the gripper a yielding updraw movement, and means acting during the updraw movement to render the pull unyielding.

9. In an upper pulling machine, the combination of an upper pulling gripper, means for giving the gripper a yielding updraw movement, and means acting in timed relation to the updraw movement to render the pull unyielding.

10. In an upper pulling machine, the combination of an upper pulling gripper, means for giving the gripper a yielding updraw movement, and means acting automatically during the updraw movement to render the pull unyielding.

11. In an upper pulling machine, the combination of an upper pulling gripper, means for giving the gripper a yielding updraw movement, and means acting automatically during the yielding movement to render the later part of the updraw pull positive.

12. An upper pulling machine having, in combination, a gripper, gripper operating mechanism for imparting a yielding pull to the upper, means becoming effective during the pull for causing the end portion of the pull to be positively effected, and means under control of the operator for varying the amount of positively effected pull.

13. An upper pulling machine having, in combination, a gripper, gripper operating mechanism for imparting a yielding pull to the upper, means becoming effective during the pull for causing the end portion of the pull to be positively effected, and means under control of the operator for relatively varying the amount of yielding and positive pull.

14. An upper pulling machine having, in combination, a gripper, gripper operating mechanism for imparting a yielding pull to the upper, means for causing the nature of the pull to be changed automatically during the pulling movement, and means under control of the operator for varying the point in the cycle when the automatic change will take place.

15. In an upper pulling machine, the combination of an upper pulling gripper, means for giving the gripper a yielding updraw movement, means acting automatically during the yielding movement to render the later part of the updraw pull positive, and means for varying the time in the updraw

movement when the updraw pull becomes positive.

16. In an upper pulling machine, the combination of an upper pulling gripper, means for giving the gripper a yielding updraw movement, means acting automatically during the updraw to render the later part of the updraw pull positive, and means under the operator's control to vary the time in the cycle during which the unyielding pull is effective.

17. A gripper lasting machine adapted to operate successively upon different portions of the margin of a shoe upper, having a gripper and gripper operating mechanism for imparting to the gripper a yielding updraw motion, a positive updraw motion and an overdraw motion, and means for imparting to the gripper a plaiting motion prior to the overdraw motion and during the positive updraw motion.

18. A gripper lasting machine that is adapted to operate successively on different portions of the margin of a shoe upper and that comprises a gripper and operating mechanism for imparting to the gripper a yielding updraw motion and a positive updraw motion, and means for imparting to the gripper an overdraw motion and a plaiting motion, said plaiting motion beginning during the positive updraw motion and continuing during the overdraw motion.

19. In a machine for working an upper over a last, the combination of means for pulling the upper variable amounts determined by the characteristics of the stock, and means for causing the pulling means to pull the upper an additional predetermined amount irrespectively of the characteristics of the stock.

20. In a machine for working an upper over a last, an updraw lever, a gripper connected thereto, a cam for operating the lever, yielding connections between the cam and the lever, and means becoming effective at a predetermined point in the cycle of the machine for causing the cam to act directly upon the lever to actuate the lever positively to pull the upper.

21. An upper pulling machine having, in combination, a gripper, gripper operating mechanism for imparting a yielding pull to the upper, and means under control of the operator for causing the yielding quality of the pull to be eliminated.

22. An upper pulling machine having, in combination, a gripper, gripper operating mechanism for imparting a yielding pull to the upper, means becoming effective during the pull for causing the end portion of the pull to be positively effected, and means under control of the operator for discontinuing the positive pull.

23. A machine for working an upper over a last, having, in combination, a gripper, gripper

operating mechanism for imparting in each cycle a yieldingly initiated pull to the upper, means becoming effective automatically during the cycle for causing the later portion of the pull to be positively effected, and means under the control of the operator for varying the time in the cycle when the positively effected pull will be initiated.

24. In a machine for working successive portions of an upper over a last progressively, the combination with a gripper constructed and arranged yieldingly to updraw, overdraw and plait the upper, of means for imparting a positive quality to the later portion of the updraw, means for initiating the plaiting movement during said portion of the updraw, upper slitting means, and means for operating the slitting means while the upper is being positively updrawn and after the plaiting movement has been initiated.

25. In a machine of the class described, the combination of a gripper for updrawing and overdrawing an upper, means for slitting the upper, and means for rendering the later portion of the updraw positive to carry the gripper away from the slitting means.

26. In a lasting machine having a gripper to which are imparted updraw, overdraw and plaiting movements, the combination of means acting automatically to cause the later portion of the updraw movement to be positively effected, means for causing the plaiting movement to be initiated during the positively effected portion of the updraw, and means for slitting the upper after the plaiting movement has begun.

27. In a lasting machine having a gripper to which are imparted updraw, overdraw and plaiting movements, the combination of power operated means for effecting the updraw at first yieldingly and then positively, upper slitting means, and means for causing the slitting means to slit the upper while the upper is positively updrawn.

28. A gripper lasting machine adapted to operate successively upon different portions of the margin of a shoe upper, having a gripper, gripper operating mechanism for imparting to the gripper a yielding updraw motion, a positive updraw motion, an overdraw motion, and a plaiting motion which is initiated prior to the overdraw motion and during the positive updraw motion, and means for slitting the upper during the plaiting motion.

29. In a machine for lasting boots and shoes, the combination of a gripper constructed and arranged to operate successively upon different portions of the margin of a shoe upper, means for operating the gripper to updraw the upper, means for operating the gripper to plait the upper, said means being constructed and arranged to initiate the plaiting movement prior to the comple-

tion of the updraw, means for imparting a positive quality to the later portion of the updraw, and means for slitting the upper operating in timed relation to the positively effected portion of the updraw.

30. A machine for working an upper over a last, having, in combination, a gripper, gripper operating mechanism for imparting a yielding pull to the upper, means for 10 imparting a positive quality to a portion of the pull, and upper slitting means operating in timed relation to the operation of said means.

31. A machine for working an upper over 15 a last, having, in combination, a gripper, gripper operating mechanism for imparting a yielding pull to the upper, means becoming effective automatically during the pull to change the quality of the pull, and means 20 for slitting the upper acting subsequently to said change.

32. A machine for working an upper over 25 a last, having, in combination, a gripper, gripper operating mechanism for imparting a yielding pull to the upper, means becoming effective automatically during the pull to increase the pull and slitting means acting to slit the upper after the increased pull has carried the gripper out of the way of 30 the slitting means.

33. A machine for working an upper over 35 a last, having, in combination, a gripper, gripper operating mechanism for imparting a yielding pull to the upper, means becoming effective during the pull for rendering the pull positive to increase the movement of the gripper, and slitting means operating after said increased movement has been sufficient to avoid contact of the slitting 40 means with the gripper.

34. A machine for working an upper over 45 a last, having, in combination, a gripper, gripper operating mechanism for imparting a yielding pull to the upper, means becoming effective during the pull for causing the end portion of the pull to be positively effected, and upper slitting means operating in timed relation to said means.

35. A machine for working an upper over 50 a last, having, in combination, a gripper, gripper operating mechanism for imparting a pull to the upper, means independent of the gripper for slitting the upper, and means for causing the pull to be automatically increased during the pulling movement and 55 prior to the action of the slitting means.

36. A machine for working an upper over 60 a last, having, in combination, a gripper, gripper operating mechanism for imparting a yielding pull to the upper, means for slitting the upper while held by the gripper, and means becoming effective automatically during the pull to change the rate of pull prior to the action of the slitting means and

65 avoid contact of the slitting means with the gripper.

37. A gripper lasting machine that is adapted to operate successively on different portions of the margin of a shoe upper and that comprises a gripper and operating 70 mechanism for imparting to the gripper a yielding updraw motion, a positive updraw motion, an overdraw motion and a plaiting motion that is effected a plurality of times during each cycle of operation of the machine, slitting means, and means to operate the slitting means during the plaiting motion.

38. A gripper lasting machine that is 75 adapted to operate successively on different portions of the margin of a shoe upper and that comprises a gripper and operating mechanism for imparting to the gripper a yielding updraw motion, a positive updraw motion, and an overdraw motion, and means 80 for imparting to the gripper a plaiting motion that is effected a plurality of times during each cycle of operation of the machine.

39. A gripper lasting machine that is 85 adapted to operate successively on different portions of the margin of a shoe upper and that comprises a gripper and operating mechanism for imparting to the gripper a yielding updraw motion and a positive updraw motion, and a wiper constructed and arranged to pause in its movement in contact with the upper prior to the positive updraw motion.

40. A gripper lasting machine that is 90 adapted to operate successively on different portions of the margin of a shoe upper and that comprises a gripper and operating mechanism for imparting to the gripper a yielding updraw motion and a positive updraw motion, a wiper, and means to cause the wiper to move into contact with the upper prior to the positive updraw motion and to complete its movement after the positive updraw motion.

41. A gripper lasting machine that is 100 adapted to operate successively on different portions of the margin of a shoe upper and that comprises a gripper and operating mechanism for imparting to the gripper a yielding updraw motion and a positive updraw motion, a wiper, and means for causing the wiper to engage the stock and press it against the edge of the shoe bottom, to pause during the positive updraw and then to wipe the upper into lasted position after the positive updraw is completed.

42. In a machine of the class described, 115 an operating lever, a cam actuated slide for operating the lever, yielding connections between the slide and the lever, a ratchet on the lever, a pawl on the slide, and stationary means controlling the pawl and allow- 120 125

ing it to engage the ratchet after a predetermined movement of the slide.

43. In a machine of the class described, a gripper, a lever for operating the gripper, a slide for operating the lever, yielding connections between the lever and the slide and means rendered operative by upper pulling movement of the slide for positively connecting the slide and lever.
- 10 44. A lasting machine having, in combination, a gripper, a spring, and means to impart pulling movements to the gripper through the medium of the spring, a cam, and cam controlled power operated means

for varying the pull imparted to the 15 gripper.

45. A machine of the class described having, in combination, a gripper for pulling a shoe upper, a power operated member for actuating the gripper, yielding connections 20 between the gripper and the member, and cam controlled means for positively connecting the gripper to the member to pull the upper.

In testimony whereof I have signed my 25 name to this specification.

ARTHUR BATES.
